UNITED STATES PATENT OFFICE.

MILTON C. TAYLOR, OF CHICAGO, ILLINOIS, ASSIGNOR TO THE WAHL COMPANY, OF CHICAGO, ILLINOIS, A CORPORATION OF DELAWARE.

MECHANICAL PENCIL.

Application filed February 14, 1921. Serial No. 444,674.

My invention relates to improvements in pencils, and is especially concerned with improvements in that type of pencil which comprises a barrel made of metal or other suitable material having a passage therein for receiving and holding the leads, and suitable means for extruding the end of the lead through one end of the barrel so that it can be used for writing.

10 The objects of my invention are:

First, to provide a pencil of this character comprising a novel means for extruding or feeding the lead from the end of the pencil, and

15 Second, to provide a pencil of the character described, which is simple of construction, economical to manufacture and easy to operate.

These and other objects will definitely appear as the description progresses, reference being had to the accompanying drawings in which:—

Fig. 1 is a longitudinal sectional view of my improved pencil,

20 Fig. 2 is a perspective view of my pencil with a portion of the barrel broken away, showing the inner or feeding mechanism in its operative position,

Fig. 3 is a disassembled view of the inner or feeding mechanism and showing their respective relation to one another,

Fig. 4 is a cross sectional view on the line 4—4 of Fig. 1,

Fig. 5 is a cross sectional view on the line 35 5—5 of Fig. 1, and

Fig. 6 is a fragmentary view of the inner barrel showing the laterally extending guide fin.

With reference to the drawings, 10 indicates the outer casing or barrel being swaged as at 11 and slotted as at 12 to form a split tip. The numeral 13 indicates an inner barrel, extending about one-half the length of the outer casing or barrel 10, the lower end 45 of said barrel 13 having a plug 14 fixedly attached thereto, and the upper end of said barrel frictionally engages the cap 15 and also forms a receptacle for the eraser 16; the said inner barrel is slightly bent or turned 50 outwardly as at 17 to form a seat for the eraser 16. The outside diameter of the inner barrel 13 is smaller than the inside diameter of the outer casing 10 by twice the thickness of the shell 18, thus causing the inner barrel, when inserted in the outer cas-

ing to fit snugly within that part of the outer barrel or casing 10 which contains the shell 18. The inner barrel 13 is prevented from being pushed down within the outer casing or barrel 10 beyond the required length by reason of another inner barrel 19. Said inner barrel or shell 19 fits snugly and is soldered to the outside barrel or casing 10, said shell 19 being of a greater thickness than the shell 18, thus preventing the barrel 13 from being pushed beyond the point of contact of the barrel 13 and the shell 19, which is at the point 20. The shell 19, as is best shown in Fig. 6, is slotted its entire length as is shown at 31, the said barrel is turned inwardly at 32 to form a fin 33, said fin 33 extending beyond the lowermost point of the barrel 19 and into the swaged portion of the outer casing or barrel 10 as shown at 34 and is cut away so as to fit snugly against the swaged portion of the barrel, the opposite side 35 forming a straight edge and runs parallel with the barrel 10 above the swaged portion.

Fixedly attached to the plug 14 is a slotted tubing 21, which extends in a downward direction to the point where the barrel is swaged at 11, said slotted tubing being threaded its entire length. The circular nut 22 is threaded interiorly and the upper portion of said nut extends outwardly forming a shoulder 23, said shoulder being about twice the circumference as the lower portion of the nut. The shoulder 23 is slotted as at 24, said slot being adapted to engage the fin. The nut 22, as will be seen, screws on to the slotted tubing 21.

A feed wire 26 is bent slightly upwardly as at 27 and 28 and between these two points the wire is so stamped as to form the two shoulders 29 and 30 on the opposite side of the feed wire. The inner mechanism is assembled as follows:

That portion of the feed wire below the shoulder 30 is first inserted into the slotted tubing 21; the nut 22 is then placed on the feed wire between the shoulders 29 and 30 and thence is screwed on to the tubing, the shoulders 29 and 30 riding in the slotted portion of the tubing; causing the nut to be securely locked between the shoulders 29 and 30. As has been explained before, the slotted tubing is fixedly attached to the plug 14, the plug in turn is attached to the barrel 13 the upper portion of which engages the cap 15. The assembled mechanism is then placed

within the barrel 10 in which is soldered the shell 19 in the lower half of the barrel and the shell 18 is soldered to the casing 10 at a determined point to which is ultimately attached the clip. Upon the insertion of the mechanism the slot 24 in the nut 22 engages the fin 33 of the shell 19. By a turning of the cap 15, which is frictionally mounted upon the inner barrel 13, in a clockwise direction, said inner barrel will also revolve in a clockwise direction and the externally threaded slotted tubing 21, being fixedly attached to said inner barrel, will be caused to revolve in the same direction, causing the nut 22 to unscrew in the direction of the tip; the feed wire 26 being attached to said nut and having shoulders riding in the slot in the tubing 21, will also pursue a downward direction, and the lead 37 being situated in the tubing 21 directly below said feed wire, will be forced out through the split tip 12.

By reversing the aforementioned operation, the said feed wire will be withdrawn and the lead can be forced back through the tubing 21.

The numeral 36 indicates a lead container, and when a new lead is desired, the cap and eraser are removed and a lead extracted. Loading the pencil is accomplished through the tip, the lead being forced into the tubing 21 until it comes in contact with the feed wire.

A clip 38 is provided. The clip per se being similar to that described in Patent No. 1,279,186 granted to John C. Wahl and William H. Odlum under date of September 17, 1918, it is not believed necessary to incumber this application with a description of said clip and its operation. However,

the flange on the clip 38 is inserted into an orifice in the outer barrel 10 and soldered to the shell 18.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variations and modifications as come within the scope of the appended claims.

Having described my invention, what I claim as new and desire to secure by Letters Patent is:—

1. In a mechanical pencil provided with a casing having a tip, a lead propeller having a lateral projection, a rotatable shell within the casing, an extension on the shell and provided with a slot through which the projection extends, an inner barrel having a fin, and a member cooperable with said fin and the extension to produce longitudinal movement of the propeller upon rotation of the shell and extension.

2. In a mechanical pencil provided with a casing having a tip, a lead propeller having a lateral projection, a rotatable shell within the casing, an extension on said shell, and provided with a slot through which the projection projects, a nut cooperable with said extension, and an inner barrel secured within the casing and cooperable with the nut for holding it against rotation but allowing its longitudinal movement for the propelling of the propeller.

In witness whereof I have hereunto subscribed my name.

MILTON C. TAYLOR.
